CLAIM

The ornamental design for a wireless charger, as shown and described.

DESCRIPTION

FIG. 1 is a top plan view of a wireless charger showing my new design;

FIG. 2 is a bottom plan view thereof;

FIG. 3 is a left side elevation view thereof;

FIG. 4 is a rear elevation view thereof;

FIG. 5 is a front elevation view thereof;

FIG. 6 is a perspective view thereof; and,

FIG. 7 is a perspective view with the charging cable in an extended state.

The broken lines shown in the drawings depict portions of the charger that form no part of the claimed design.
